US00D896213S

(12) **United States Design Patent** (10) **Patent No.:** **US D896,213 S**
Lee et al. (45) **Date of Patent:** **** Sep. 15, 2020**

(54) **CASE FOR ELECTRONIC DEVICES**(71) Applicant: **SPIGEN KOREA CO., LTD.**, Seoul (KR)(72) Inventors: **Jong Hwa Lee**, Seoul (KR); **Bum Joon Lee**, Seoul (KR)(73) Assignee: **Spigen Korea CO., LTD.**, Seoul (KR)(***) Term: **15 Years**(21) Appl. No.: **29/722,559**(22) Filed: **Jan. 30, 2020****Related U.S. Application Data**

(63) Continuation of application No. 29/641,935, filed on Mar. 26, 2018, now Pat. No. Des. 877,133.

(51) **LOC (12) Cl.** ..... **14-03**(52) **U.S. Cl.** ..... **USPC** ..... **D14/250**(58) **Field of Classification Search**

CLAIM

The ornamental design for a case for electronic communications device, as shown and described.

DESCRIPTION

FIG. 1 is a front perspective view of a case for electronic devices, comprised of an inner shell, upper outer frame, and lower outer frame, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is an enlarged top plan view thereof;

FIG. 8 is an enlarged bottom plan view thereof;

FIG. 9 is a front perspective view of the inner shell, shown isolated from the case for electronic devices for clarity;

FIG. 10 is a rear perspective view of the inner shell, shown isolated from the case for electronic devices for clarity;

FIG. 11 is a front perspective view of the upper outer frame, shown isolated from the case for electronic devices for clarity;

FIG. 12 is a rear perspective view of the upper outer frame, shown isolated from the case for electronic devices for clarity;

FIG. 13 is a front perspective view of the lower outer frame, shown isolated from the case for electronic devices for clarity;

FIG. 14 is a rear perspective view of the lower outer frame, shown isolated from the case for electronic devices for clarity;

FIG. 15 is a front exploded perspective view of the case for electronic devices; and,

FIG. 16 is a rear exploded perspective view of the case for electronic devices.

The broken lines depict portions of the case for electronic devices that form no part of the claimed design.
